AUTOMATIC DOCUMENT FEEDING APPARATUS FOR XEROGRAPHIC REPRODUCING MACHINES OR THE LIKE

Stephen R. Anderson, Rochester, Melvin G. Crandell, Walworth, and Donald L. Pease, Marion, N.Y., assignors to Xerox Corporation, Rochester, N.Y., a corporation of New York

Filed June 10, 1968, Ser. No. 12,278

Term of patent 14 years

Int. Cl. D16—05

U.S. Cl. D61—1

Des. 214,959

PAGE 3

FIG. 2

FIG. 3

FIG. 4

FIG. 5

FIG. 1 is a front perspective view of an automatic document feeding apparatus for xerographic reproducing machines or the like showing our new design; the broken lines representing the xerographic reproducing unit is shown for illustrative purposes only;

FIG. 2 is a front elevational view thereof;

FIG. 3 is a right-hand elevational view thereof;

FIG. 4 is a left-hand side elevational view thereof; and

FIG. 5 is a top plan view thereof.

The rear side of the apparatus is substantially a mirror image of the front side and the bottom of the machine is substantially plain and unornamented.

We claim:

The ornamental design for an automatic document feeding apparatus for xerographic reproducing machines or the like, as shown and described.
